UNITED STATES PATENT OFFICE.

CHARLES HASPER, OF BRIDGEPORT, OHIO.

HATPIN GUARD.

1,409,714.

Specification of Letters Patent. Patented Mar. 14, 1922.

Application filed November 22, 1921. Serial No. 516,919.

To all whom it may concern:

Be it known that I, CHARLES HASPER, a citizen of the United States of America, and resident of Bridgeport, county of Belmont, 5 and State of Ohio, have invented certain new and useful Improvements in Hatpin Guards, of which the following is a specification.

This invention relates to a hat-pin guard, and it has for its primary object to provide a 10 simple, inexpensive and practical device whereby the pointed ends of hat pins are shielded and whereby such pins are effectually retained against chance withdrawal.

In describing the invention in detail, reference is herein had to the accompanying drawings, in which—

Figure 1 is a side elevation of a hat pin equipped with my improved guard;

Figure 2 is an enlarged longitudinal section of the guard;

Figures 3 and 4 are sections taken, respectively, on lines 3—3 and 4—4, Fig. 2; and—

Figures 5 and 6 are enlarged views of two 25 different types of points for the shaft of the pin.

Referring to said drawings, 1 indicates the shaft of the pin which may either have a reduced neck 2 slightly rearward of its point, as shown in Figs. 2 and 6, or may have its 30 point of approximately spear-head form with its butt portion slightly exceeding in diameter that of the shaft, as shown at 3 in Fig. 5.

The guard forming the present invention 35 comprises an approximately cylindrical body 4 of metal or other suitable material which constitutes a sheath for the pointed end of the pin, said sheath having an axial bore 5 of suitable length extending thereinto 40 for the reception of said pin-point. Extending diametrically through said sheath is a rectangular orifice 6 in which is slidably disposed a sheet-metal plate or tongue 7 which is attached at its outer end to a laterally directed terminal arm 8 formed upon an end member 9 of a coil spring 10. Said spring is disposed within the outer end of a channel-like recess 11 provided in a side of the sheath 4 and is carried by a transverse 45 pin 12 which has its opposite ends mounted in said sheath at opposite sides of said recess. The opposite end member 13 of said spring 10 rests upon the bottom of said recess, extending inwardly along said bottom.

50 An aperture 14 is provided in the tongue 7 at a point which, in the normal elevated po-

sition of said tongue, is located above the level of the bore 5, said aperture being of a width or diameter approximating that of said bore and being adapted, when in register with said bore, to permit the pointed end of the pin to pass therethrough. Leading longitudinally downward from said aperture 14 is a slot 15 having a width sufficiently great to receive therein, when the pin is of the form shown in Figs. 2 and 6, the reduced neck portion 2, but of insufficient width to permit retraction therethrough of the pointed end; or, when the pin has the enlarged pointed-end form shown in Fig. 5, the width 60 of said slot is insufficient to permit retraction therethrough of the enlarged pointed end. The aperture 14 and slot 15 together 65 form an opening or slot of keyhole form, hereinafter termed a keyhole-slot.

As is apparent from the foregoing, in order to effect application or removal of the guard, the tongue 7 must be depressed against the tension of its supporting spring 10 to a point at which the aperture 14 is 70 aligned with the bore 5. Following application, the spring maintains the tongue elevated to a position in which the pin-shank is received in the lower end portion of the keyhole slot and in which, consequently, chance 75 detachment of the sheath is effectually prevented.

To facilitate application of the guard, the inner end of the sheath has formed therein a 80 conical recess 16 forming a guideway leading to the adjacent end of the bore 5, as shown.

What is claimed is—

1. A hat-pin guard comprising, in combination with a hat-pin having a portion 95 located rearward of its pointed end of relatively reduced diameter, a body member adapted for mounting in sheathing relation to said pointed end, said member having a longitudinal point-receiving bore 100 therein and also having an orifice transversely crossing said bore, a tongue 105 slideable in said orifice and having therein a keyhole slot through which said pointed end of the pin projects, and a spring normally maintaining said tongue in a position in which the reduced portion of the pin is received by the narrower portion of the slot, said tongue being depressible to position the larger end of the slot in alignment with the bore of said body member.

2. A hat-pin guard comprising, in com-

bination with a hat-pin having a portion located rearward of its pointed end of relatively reduced diameter, a body member adapted for mounting in sheathing relation to said pointed end, said member having a longitudinal point-receiving bore therein and also having an orifice transversely crossing said bore, a tongue slidable in said orifice and having therein a keyhole slot 5 through which said pointed end of the pin projects, and a spring mounted on said body member, said spring having a portion disposed in supporting relation to said tongue and normally holding the latter in 10 a position wherein the narrower portion of said slot receives the reduced portion of the pin, said tongue being depressible to a position in which the larger end of said slot aligns with the bore of the body members.

20 3. A hat-pin guard comprising, in combination with a hat-pin having a reduced neck located rearward of its pointed end, a body member adapted for mounting in sheathing relation to said pointed end, said member having therein a longitudinal point-receiving bore and an orifice crossing said bore, a tongue movable in said orifice and having a longitudinal keyhole slot therein, 25 said member also having a recess in a side thereof, a pin crossing said recess, a coil spring carried by said pin within said recess and having a portion disposed in yieldingly supporting relation to said tongue whereby the latter is normally held in a position in which the reduced neck of the hat-pin is received by the narrower portion 30 of said keyhole slot, said tongue being depressible against the tension of said spring to position the wider portion of said slot in alignment with the bore of the body member.

30

tioning the wider portion of said slot in 35 alinement with the core of the body member, said member having therein a recess in which said spring is mounted.

4. A hat-pin guard comprising, in combination with a hat-pin having a reduced neck located rearward of its pointed end, a body member adapted for mounting in sheathing relation to said pointed end, said member having therein a longitudinal point-receiving bore and an orifice crossing said bore, a tongue movable in said orifice and having a longitudinal keyhole slot therein, 40 said member also having a recess in a side thereof, a pin crossing said recess, a coil spring carried by said pin within said recess and having a portion disposed in yieldingly supporting relation to said tongue whereby the latter is normally held in a position in which the reduced neck of the hat-pin is received by the narrower portion 45 of said keyhole slot, said tongue being depressible against the tension of said spring to position the wider portion of said slot in alignment with the bore of the body member.

60 In testimony whereof, I affix my signature in presence of two subscribing witnesses.

CHARLES HASPER.
